UNITED STATES PATENT OFFICE.

JOHN E. WALSH, OF WASHINGTON, DISTRICT OF COLUMBIA.

LOCKING SYSTEM FOR MAIL-BOXES.

SPECIFICATION forming part of Letters Patent No. 718,553, dated January 13, 1903.
Application filed May 20, 1902. Serial No. 108,284. (No model.)

To all whom it may concern:

Be it known that I, JOHN E. WALSH, of Washington, District of Columbia, have invented certain new and useful Improvements 5 in Locking Systems for Mail-Boxes, of which the following is a complete specification.

My invention relates to certain new and useful improvements in locking systems for receptacles, and principally for mail-boxes, 10 and constitutes an improvement on the invention for which Letters Patent were issued to me under date of May 6, 1902, No. 699,597. As with the invention of said patent this invention has also for its object to provide 15 means whereby a mail-collector or other proper person will be compelled to visit and collect from each receptacle or a mail-box on the route in the regular prescribed order, the opening of any one box in the series being 20 dependent on the previous opening of the box immediately preceding. In accomplishing this object I provide each mail-box in the route with a lock substantially the same as the other locks in that route, the exception 25 being that a certain part, hereinafter referred to as a "barrier," is turned to a different position from the corresponding barriers of the other locks. I mount a key on a portable key-carrier and provide it with an adjustable 30 guard, which is adapted to be changed in its relative position with the successive operations of a series of keys, hereinafter called "carrier-keys." The guard is designed to co-act with the barriers of the box-locks to prevent 35 the operation of such box-locks except when the guard is in the proper position to pass the barriers. The several carrier-keys are confined in the receptacles or mail-boxes along the route, each being contained in the 40 receptacle or box immediately preceding the receptacle or box for which it is adapted to adjust the guard of the box-key in position for operating the lock thereof. By this arrangement the mail-collector starts his trip 45 with the box-key in position for operating the lock of the first box on his route only, and after removing the contents of that box he inserts the carrier-key found therein and turns the guard or box key into position for 50 operating the lock of the second box, at the same time locking the box-key in that position. This operation is continued in regular

order until all the mail-boxes have been visited. When the last box has been visited, the use of the key therein turns the guard or box 55 key into position for operating the first box at the next collection. It will thus be seen that the carrier must have previously visited and opened the box immediately preceding in order that he may open any box in his route, 60 thereby insuring a faithful performance of the duties of his position, which consist in collecting from each and every box in his route in regular order on each trip, and rendering impossible that any box shall be overlooked, either by intention or mistake, as if such be the case the collector would be unable to open any box following the one overlooked, or, in fact, any box in the series, without first going back to said box. 70

With the above and other objects in view the invention consists in the novel details of construction and combination of parts, which are clearly set forth in the following specification and particularly pointed out in the 75 claims at the end of the description.

Referring to the accompanying drawings, in which similar characters of reference are used to denote similar parts in each of the several views, Figure 1 is a perspective view of an 80 open mail-box, exposing to view the key confined therein. Fig. 2 is a sectional elevation of the box-key and carrier. Fig. 3 is a transverse section thereof. Fig. 4 is an end elevation of the box-key and carrier. Fig. 5 is 85 a side elevation of a padlock for use in connection with my device, and Fig. 6 is an elevation of the box-key and carrier on a reduced scale.

In the drawings, 1 indicates a cylindrical 90 casing or "box-key carrier," so called, as being analogous to the key-carrier of my above-mentioned patent, and which casing is preferably made of thin metal or other light material. 95

At one end of the carrier is a disk plate 2, riveted or otherwise rigidly secured thereto and having a tubular stem 3 projecting therefrom which carries diametrically-opposed key-blades 4. 100

A solid cylindrical core 5 is journaled at both ends in the ends of the carrier 1, with one of its trunnions 6 projecting through a circular opening in the end of the carrier

and fitting within the stem 3, where it has a tapering projection 7, which extends toward the mouth of the tubular stem 3 and is semi-circular in cross-section. This projection is 5 herein referred to as the "guard," which is adjusted with relation to the remainder of the key.

A shaft 8 extends from one end of the carrier 1 to the other end and has pivotally mounted 10 upon it a number of pawls or detents 9, each being pressed upon by a spring 10 and having a hooked end to engage within one of the notches 11, which are arranged spirally about the core 5. Diametrically opposite 15 each notch 11 is a lug 12, projecting from the core 5, and these of course are likewise arranged in a spiral formation about the core. The lugs 12, however, are not in the same sectional plane as the notches 11, being set 20 so as to lie within sectional planes located intermediate of adjacent notches 11. A series of key-openings 13 are arranged in a straight line along the carrier 1 and each has a key-guide 14 leading therefrom toward the 25 core 5.

The carrier-keys 15 are confined within the mail-boxes 16 by means of chains or in any other suitable manner and are provided with straight back 17 to slide upon the key-guides 14, and their opposite edges are curved 30 to form cams 18 to ride beneath and lift the pins 19, projecting from one side of the pawls 9, to raise the hooked ends of said pawls out of engagement with the notches 11 just prior 35 to the engagement of their ends 20 with the lugs 12.

The mail-box key is of that sort which only has to be pressed into the opening of the lock to open same—that is, no turning of the key 40 within the lock is necessary. Hence it will be seen that the guard 7 will freely pass the similarly-shaped barrier 7' of the lock when said guard is turned to the proper angle with relation to the remainder of the key. However, if the guard should be at any other angle the guard and barrier would conflict and prevent the insertion of the key.

The insertion of the proper key 15 in its slot 13 first elevates the pawl 9 out of engagement with the notch 11, so that the core 5 is free to be rotated. Then the end 20 comes into contact with the lug or projection 12 opposite said notch and gives the core a partial rotation until the next succeeding pawl 9 is 55 forced by the spring into its notch 11, when the core is again locked against further rotation, and the box-key is adjusted to fit only the lock of the following box in the route by reason of the new position of the guard 7.

60 The operation of the device will be readily understood from the foregoing description. The collector on leaving the post-office for his collection takes with him the carrier, with the guard of the box-key in position for opening the lock of the first box in the route. When this box has been opened and the contents removed, he employs the key found

therein to turn the core 5, so as to change the angle of the guard 7 to the position in which it will operate the lock of the second box. 70 The operation is continued throughout the remaining boxes of the route until when the key in the last box is used it turns the core and guard back to their original position for operating the lock to the first box, the core 75 in the meantime having made a complete revolution.

It will be understood, of course, that the notches 11 and lugs or projections 12 are arranged around the box-key in accordance 80 with the number of boxes in the route in such manner as that the box-key will have made a complete revolution on each circuit of the boxes. It will also be observed that instead of the lugs or projections 12 the box-key may 85 be provided with notches upon which the carrier-key acts instead of the lugs.

Various details of construction may be made without departing from the spirit and scope of my invention, and hence I do not 90 desire to be limited to the exact construction herein shown and described.

Having thus fully described my invention, what I claim as new, and desire to secure by Letters Patent of the United States, is— 95

1. In a locking system for a series of receptacles, the combination with a portable carrier adapted to hold the key to said receptacles, of means located at each of said receptacles for adjusting said key to a position for use at 100 the next receptacle in the series.

2. The combination with a portable carrier adapted to hold the key to a series of receptacles, of adjusting means located within each of the receptacles for adjusting the key to a 105 position for use at the next receptacle in the series.

3. In a locking system for a series of receptacles, the combination with a portable carrier, of an adjustable key adapted to open 110 one receptacle only in the series in each of its several adjustments, and means located at each of the receptacles for changing the position of the key to adapt it to open the next succeeding receptacle. 115

4. In a mail-box-locking system, the combination with a portable carrier, containing means adapted to open all the boxes in the system, a guard carried by said means and means located at each box for changing the 120 position of the guard to permit the opening of the next box in the series.

5. In a mail-box-locking system, the combination with a portable carrier holding a key adapted to open all the boxes in the system, 125 an adjustable guard carried by said key and means located at each box for changing the position of the guard to permit the key to open the next receptacle.

6. In a device of the character described, a 130 casing, a key mounted thereon, a core journaled in the casing, a guard carried by said core, a series of pawls pivoted in the casing and adapted to engage in notches in the core,

in combination with keys adapted to be inserted through openings in the casing to release the pawls from engagement with the notches and give the core a partial rotation.

5 7. In a device of the character described, a casing, a key mounted thereon, a core journaled in the casing, a guard carried by said core, a series of pawls pivoted in the casing, notches in the core and springs adapted to 10 press said pawls into engagement with said notches, in combination with keys adapted to be inserted through openings in the casing to release the engagement of the pawls with the notches and give the core a partial rotation.

15 8. In a device of the character described, a

casing, a key mounted thereon, a core journaled in casing, a guard carried by said core, a series of spring-pressed pawls pivoted in the casing adapted to engage in notches in 20 the core, and lugs projecting from the core, in combination with keys adapted to be inserted through openings in the casing to release the engagement of the pawls with the notches and give the core a partial rotation 25 by pressing against the lugs.

In testimony of all which I have hereunto subscribed my name.

JOHN E. WALSH.
